UNITED STATES PATENT OFFICE.

FREDERICK DIEHL, OF ELIZABETH, NEW JERSEY, ASSIGNOR TO DIEHL MANUFACTURING COMPANY, OF ELIZABETH, NEW JERSEY, A CORPORATION OF NEW JERSEY.

GYRATORY FAN.

Application filed April 27, 1928. Serial No. 273,187.

This invention relates to electric fans, more particularly of the gyratory type disclosed in the patent to F. Diehl, No. 1,099,693, of June 9, 1914, and has for an object to provide means 5 for maintaining at all times efficient traction between the traction-wheel and the wheel runway of a fan of this type.

According to the present improvement a gyratory link or thrust-bar is provided to hold the wheel in driving contact with the track. One end of this bar is rotatably connected to a gyratory center on the stationary frame support. The other end of the bar is connected to the fan-motor frame at the driving wheel axis; the sole function of such bar being to hold the driving wheel pressed upon the track. Preferably there is incorporated in the bar a spring-pressed pin which 15 yieldingly bears upon the center connection and, by reaction, presses the bar away from such connection and causes the traction-wheel to be yieldingly pressed upon the track. The spring-pin affords a resilient thrust-connection 20 between the fan-frame and the stationary-frame.

In the accompanying drawings, Fig. 1 is a side elevation, partly in section, of an electric fan embodying the invention. Fig. 2 is a section on the line 2—2, Fig. 1. Fig. 3 is a plan view of the speed-reduction gearing which connects the traction-wheel with the fan-motor shaft, and Fig. 4 is a perspective view of the thrust-member which holds the traction-wheel in driving engagement with the track-way.

According to the preferred embodiment of the invention illustrated, 1 is a base having holes 2 for attaching screws and downwardly extending bolts 3 by which the inverted cup-shaped frame 4 is secured to the base 1; this assembly constituting a stationary frame support in which the fan-motor frame 5 is universally mounted by being pivoted on trunnion-screws 6 carried by the ring 7 which is pivoted on trunnion screws 8 carried by the frame 4. The fan-motor frame has journaled in it the usual fan-shaft 9 carrying at its lower end the fan-blades 10 and at its upper end the worm 11.

The worm 11 meshes with the gear 12 on the cross-shaft 13 journaled in bearing bosses 14 in the cup-shaped end-portion 15 of the fan-motor frame. The cross-shaft 13 has fixed to it a worm 16 which meshes with the gear 17 on the shaft 18 journaled in the plate

19 secured by screws 20 in the frame end-portion 15. The shaft 18 has fixed to it a gear 21 which meshes with the gear 22 on the shaft 23 journaled in the cap-member 24. Fixed to the shaft 23 is the cylindrical hub 25 of the traction-wheel 26 having the rubber-tired rim 27 which runs on the circular track-way 28 formed on the ring 29 secured by screws 30 to the frame 4.

The frame 4 has secured to it, at the axis 65 of gyration $a-b$ of the fan 5, a cylindrical stud 31 which is embraced by the forked end 32 of the link or thrust-member 33, the opposite forked end 34 of which embraces the cylindrical hub 25 of the traction-wheel 26. 70 The thrust-member 33 comprises two angularly related arms 35 and 36, the angle of which is the supplement of the angle between the motor-shaft 9 and the axis of gyration $a-b$.

The thrust-member 33 preferably has mounted in it a spring-pressed pin 37 which bears against the center-stud 31 and expands the thrust-member in effective length, causing the arm 36 thereof to press upon the side 80 of the hub 25 and force the traction-wheel 26 against the track-way 28. Due to the resilient means between the stud 31 and track-way 28, and the angular relation of the wheel axis and the axis of gyration, the arm 35 of the 85 link 33 is, by reaction, caused to bear upwardly against the flat bearing surface 38 within the frame 4; such bearing surface being parallel to and spaced from the plane of the track-way 28.

A washer 39, larger than the stud 31, is secured to the latter by the center screw 40 to hold the inner end of the link 33 from dropping away from the stud 31.

It will be observed that the side pressure 95 is imparted to the traction-wheel 26 by the gyratory thrust-member 33 independently of the wheel-rim 27, which latter is not subjected to frictional wear other than that caused by its continuous rolling engagement 100 with the track-way. The fan is found to be very quiet in operation, which is an important desideratum not found in crank- or gear-driven gyratory fan-motions.

Having thus set forth the nature of the 105 invention, what I claim herein is:—

1. In a gyratory fan, in combination, a supporting frame having a circular track-way, a fan-motor having a frame universally mounted in said supporting frame, a trac- 110

tion-wheel journaled in the fan-motor frame and connected to be driven by the fan-motor, and a gyratory thrust-member connected at its opposite ends to said frames and operating to hold the traction-wheel in driving engagement with said track-way.

2. The combination set forth in claim 1 in which the thrust-member includes means for yieldingly expanding its effective length.

10 3. The combination set forth in claim 1 in which the thrust-member includes a spring expansion element.

15 4. The combination set forth in claim 1 in which the supporting frame and fan-motor frame carry center members and in which the thrust-member is forked at its opposite ends to embrace said members.

20 5. The combination set forth in claim 1 in which the thrust-member is formed with two angularly related arms, the angle of which is the supplement of the angle between the fan-motor axis and the axis of gyration of the fan-motor.

25 6. In a gyratory fan, in combination, a supporting frame having a circular track-way, a fan-motor frame universally mount-

ed in said supporting frame, a traction-wheel journaled on the fan-motor frame and adapted to run on said trackway to impart a gyratory movement to the fan-motor frame, a 30 stud on the supporting frame at the axis of gyration, a hub on the traction-wheel, and a thrust-bar bearing at its opposite ends upon said stud and hub.

7. In a gyratory fan, in combination, a 35 supporting frame having a circular track-way and a bearing surface in a plane parallel to and spaced from the plane of the track-way, a fan-motor frame universally mounted in said supporting frame, a traction-wheel 40 journaled on the fan-motor frame and adapted to run on said track-way to impart a gyratory movement to the fan-motor frame, and resilient means between the center of said bearing surface and the track-way, said 45 means including a thrust-bar connected at its opposite ends to said center and the axis of the traction-wheel and bearing sidewise against said bearing surface.

In testimony whereof, I have signed my 50 name to this specification.

FREDERICK DIEHL.
